UNITED STATES PATENT OFFICE.

CLYDE C. REAVEL, OF MARION, INDIANA.

WRENCH.

1,396,590.

Specification of Letters Patent. Patented Nov. 8, 1921.

Application filed September 16, 1920. Serial No. 410,693.

To all whom it may concern:

Be it known that I, CLYDE C. REAVEL, a citizen of the United States of America, residing at Marion, in the county of Grant 5 and State of Indiana, have invented new and useful Improvements in Wrenches, of which the following is a specification.

The object of the invention is to provide a simple and efficient and at the same time 10 useful wrench having in addition to an effective leverage when in operation, a convenient means of adjustment of the movable jaw whereby the positioning of the latter with relation to the fixed jaw, for engagement with an interposed object, may be effected unassisted by the hand which grasps the operating grip of the wrench, and with these objects in view, the invention consists 15 in a construction and combination of parts, 20 of which a preferred embodiment is shown in the accompanying drawing, wherein:—

Figure 1, is a side view of a wrench embodying the invention.

Fig. 2 is a longitudinal sectional view of 25 the same.

Fig. 3 is a rear view of a portion of the wrench to show the means for locking the swivel grip.

Fig. 4 is a perspective view of the sleeve 30 member of the movable jaw.

The wrench consists essentially of a shank 10 carrying the fixed jaw 11 and provided at the opposite end with an enlargement 12 which is threaded to form a feed screw, a 35 movable jaw 13 having keepers 14 which are mounted to slide upon the shank in the opening and closing movements of the jaws and a swivel grip or handle 15 intermediately threaded for engagement with the feed 40 screw 12 and having an internal groove 16 for engagement with the lip 17 of the inner end of the sleeve 18 of the movable jaw. Obviously the adjustment of the movable jaw is effected by feeding movement of the 45 movable or swivel grip or handle through action of the latter upon the feed screw 12 and when the jaws have been brought into contact with opposite sides of an object to be grasped, a vigorous turing movement 50 of the grip will serve to bind the jaws upon the object in a manner similar to that which is common to a pipe or rod wrench so that even with flat faced jaws, the apparatus described is adapted in a measure to perform 55 the functions of a pipe wrench. Obviously

the power with which the grip can be effected will depend upon the pitch of the threads of the feed screw. Owing to the fact that the adjustment of the movable jaw is effected by the turning of the grip or 60 handle with relation to the jaws and the shank provides for the opening or closing movement of the jaws by the hand which grasps the grip or handle without necessitating the holding of the head of the wrench 65 with the other hand.

When the desired adjustment of the jaws has been effected to grasp an interposed object, the swivel grip may be locked against 70 rotation by means of an eccentric lock 19 mounted upon the sleeve of the movable jaw for engagement with the extremity of the grip or handle as shown clearly in Fig. 3.

The use of an eccentric lock for the handle, such as shown, makes for the ready 75 release of the wrench from a nut with one hand in case the jaws have become bound on the nut. Turning the handle in a reverse direction from that in which it is turned to tighten the movable jaw, tends to swing the 80 eccentric 19 out of locking position and thus makes it unnecessary to remove the working hand or else use the other hand to first release the lock, such as is the case where positive locks are employed. Again the use of 85 an eccentric lock, such as shown, because of its frictionally engaging the handle provides for the nicest adjustment of the two jaws which is not possible where positive locking elements have to be engaged with 90 each other.

The invention having been described, what is claimed as new and useful is:—

A wrench having a shank carrying a fixed jaw and provided at the opposite end from 95 the jaw with a feed screw, a movable jaw provided with a sleeve slidably mounted on the shank of the fixed jaw, a grip or handle interiorly threaded for engagement with the feed screw and having an internal 100 groove adjacent its upper end slidably engaging a lip on the inner end of the sleeve, and a locking device consisting of an eccentric disk pivotally mounted on said sleeve and engageable with the upper end of the 105 handle in the manner and for the purpose specified.

In testimony whereof I affix my signature.

CLYDE C. REAVEL.
